Howard E. Barton

UNITED STATES PATENT OFFICE.

ARTHUR G. EKLOF, OF PROVIDENCE, RHODE ISLAND.

NUMBER-PLATE HOLDER.

1,403,073.

Specification of Letters Patent. Patented Jan. 10, 1922.

Application filed January 15, 1921. Serial No. 437,560.

To all whom it may concern:

Be it known that I, ARTHUR G. EKLOF, a citizen of the United States, residing at Providence, in the county of Providence and State of Rhode Island, have invented certain new and useful Improvements in Number-Plate Holders, of which the following is a specification.

This invention relates to number-plate holders adapted to be adjusted to embrace plates of different sizes; and the object of this invention is to provide such a holder more particularly adapted to carry number plates for motor vehicles, the same being constructed of four corner sections, each section being provided with a pair of arms extending at right angles to each other, and the arms of the different sections being adjustably connected together, each section being also provided with a pocket for the reception of the corners of the plate.

A further object of this invention is to raise the plate corner-receiving pockets above the plane of its arms sufficiently to support the plate clear of the heads of the connecting bolts to prevent the plate from rattling against the bolt heads while vibrating.

A still further object of the invention is to provide flexible pads in the corner pockets to bind the corners of the plate and so again prevent rattling.

With these and other objects in view, the invention consists of certain novel features of construction, as will be more fully described, and particularly pointed out in the appended claims.

In the accompanying drawings:

Figure 1 is a front elevation of my improved adjustable number-plate holder, illustrating the outline of the number plate in dotted lines.

Figure 2 is a section on line 2—2 of Figure 1, looking in the direction of the arrow.

Figure 3 is a section on line 3—3 of Figure 1, looking in the direction of the arrow and illustrating the bracket by which the holder is secured in position on the frame of a vehicle.

Figure 4 is a perspective view illustrating one of the plate-receiving corner pockets.

With reference to the drawings, 10 designates the different corner sections of my improved number-plate holder, each section being provided with two arms, a long arm 11 and a short arm 12. Each of these arms

is slotted longitudinally as at 13, and each arm of each section overlaps the corresponding arm of the next adjacent section, and a binding bolt 14 is passed through the slots 60 of both overlapping arms to bind these arms together in adjusted position.

In order to hold the ends of these arms in line with each other, I have provided a lug 15 on the end of each arm, shaped to 65 extend up into the slot of the next arm; by which construction but a single binding bolt in each pair of arms is necessary to maintain alignment.

Each of these corner sections is provided 70 with a corner pocket 16 which is raised by the short-necked portion 17 above the plane of its arms and a pad 18 is positioned in the bottom of each pocket to serve as a cushion against which the number plate 19 rests to 75 prevent rattling of the plate in these corners.

Then again it will be noted that by raising these corner pockets a sufficient distance above the plane of the arms the plate will be clear of the bolts 14, sufficiently, so as not to 80 strike thereagainst during the constant vibration caused by the running vehicle.

In practice plates carrying the low numbers are much smaller than those carrying the higher numbers or multiplicity of characters. Therefore it is found desirable to make the plate holders adjustable to accommodate these different sized plates.

When a plate is positioned in a holder it is only necessary to loosen the four bolts, expand the parts sufficiently to pass the corners of the plate into the four corner pockets, after which the sections are forced together to bind the plate firmly in position and the bolts 14 set up to bind the whole 95 permanently in position.

In order to connect the holder to the frame of a vehicle I have shown rearwardly-extending bracket 20 having a clamping member 21 adapted to be set tightly onto 100 the part 22 by means of a bolt 23.

The device is extremely simple and practical in construction and effective in its operation and by its use only the faces of the rounding pockets are visible, the rest of the 105 frame being concealed behind the plate.

The foregoing description is directed solely towards the construction illustrated, but I desire it to be understood that I reserve the privilege of resorting to all the mechanical changes to which the device is susceptible, the invention being defined and

limited only by the terms of the appended claims.

I claim:

1. A number-plate holder comprising a frame having four sections each having a pair of arms extending at right angles to each other, connecting members for securing said arms to the complementary arm of the adjacent section, and each section having a plate-receiving corner pocket raised above the plane of its arms sufficiently to support the plate thereon above said arm-connecting members.

2. A number-plate holder comprising a

frame having four separate corner sections, 15 each section having a corner pocket for the reception of the corners of the number plate, anti-rattling pads in said pockets, each of said corner sections being provided with a pair of arms extending at right angles to each other, each arm being slotted and overlapping that of the next adjacent complementary arm, bolts for adjustably securing together said complementary arms, and means in said arms for holding said arms in alignment with each other.

In testimony whereof I affix my signature.

ARTHUR G. EKLOF.
